CLESSIE L. CUMMINS, OF COLUMBUS, INDIANA.

CIRCULATING-FUEL SYSTEM FOR OIL ENGINES.

Application filed September 27, 1921. Serial No. 503,679.

To all whom it may concern:

Be it known that I, CLESSIE L. CUMMINS, a citizen of the United States, and a resident of Columbus, county of Bartholomew, and State of Indiana, have invented a certain new and useful Circulating-Fuel System for Oil Engines; and I do hereby declare that the following is a full, clear, and exact description thereof, reference being had to the accompanying drawings, in which like numerals refer to like parts.

This invention relates to an oil engine for burning heavy fuel of the type wherein the fuel is burned by the heat of the air compressed by the piston within the combustion chamber. With this type of engine, pure air is drawn into the cylinder and heated therein by compression to a very high degree, the hot air entering a fuel cup through a small port therein. At the same time this heat is transmitted through the holes and walls of the fuel cup, vaporizing part of the fuel oil which is discharged therein, so that this vapor ignites by reason of the high degree of heat and explodes within the fuel cup. The force of such explosion inside of the cup separates the remaining fuel liquid into tiny particles, driving it out in a fine spray into the combustion chamber. This highly atomized fuel encounters the incandescent heat created in the cylinder, ignites and completely burns. This causes the air in the cylinder to expand many times its normal volume under compression, driving the piston on its power stroke.

Heretofore in oil engines of this type the heavy oil enters the fuel cup by gravity, passing through a port in the injector head and is controlled in volume by a valve for that purpose. Difficulty has been experienced with this construction wherein the crude oil used in the engines contains a high percentage of gasoline, such as is found in the oil fields. It is, therefore, the purpose of this invention to so construct the injector and evolve a principle of fuel supply therein, as will cause the engine to be operated not only by kerosene or a fuel with a low percentage of gasoline, but also any fuel regardless of the percentage of gasoline which it may contain.

Where fuel oil is employed having a high percentage of gasoline, the extreme heat of the engine causes the gasoline particles to be vaporized within the fuel inlet

and before reaching the fuel cup. Gas is given off by reason of such vaporization and forms a gas pocket around the fuel valve and inlet, the passageway therethrough being so small that the gas pocket created therein prevents the liquid fuel from passing therethrough into the fuel cup. Therefore, where engines of this type are used in the oil fields or other places where it is desired to use crude oil having a high percentage of gasoline, the engine will operate for a few minutes and then gas will form, stopping the flow of fuel to the cup, thereby choking the engine for lack of fuel supply. To overcome this difficulty, this invention contemplates an arrangement whereby the fuel will be maintained in circulation through the injector head and fuel valve so as to carry away all foreign matter, dirt and any gas formed in the fuel valve or passageway and maintain a clear passage for the liquid fuel to enter the fuel cup. Such circulation of the fuel through the injector also aids in eliminating carbon from being deposited by reason of the intense heat about the fuel and air valve therein, as the constant passage of fuel therethrough carries off a portion of the heat and tends to maintain such valves in a relatively cool condition.

The full nature of the invention will be understood from the accompanying drawings and the following description and claims.

In the drawings, Fig. 1 is a side elevation of the stationary type of oil engine embodying this invention. Fig. 2 is a plan view looking down upon the fuel injector and plug. Fig. 3 is a section taken on the line 3-3 of Fig. 2 showing a vertical section through the injector plug. Fig. 4 is a perspective view of the injector plug with a quarter section cut therefrom illustrating the fuel circulating passageway.

In the drawings there is shown an oil engine supported by the base 10 in which is contained a fuel reservoir 11. The base 10 supports a cylinder 12 upon which is mounted a water hopper 13 for providing a water cooling medium to the cylinder. Supported upon the base 10, there is a bearing 14 in which is mounted a crank shaft 15 having a fly wheel 16 secured to one end thereof and a connecting rod 17 pivoted to said crank shaft at one end and to the re-

ciprocating piston at the other end. This construction is of the usual type commonly found in the stationary oil engines.

The fuel is delivered to the fuel injector 5 plug through the auxiliary fuel tank 18 into which fuel is pumped by the reciprocating flange 19 through the pump 20 and the fuel pipe 21. There is provided an overflow pipe 22 extending into the fuel tank 18 near the 10 top thereof so as to cause an excessive amount of fuel pumped therein to flow back into the main fuel reservoir 11. The fuel flows by gravity from the tank 18 through the fuel line 23 to the fuel injector plug 15 which will be hereinafter described in detail, and the overflow fuel returns from the fuel plug through the overflow pipe 24 to the overflow pipe 22 and back to the reservoir 11. The pump plunger 19 is actuated 20 by means of a finger 25 secured to the valve push rod 26, said push rod being actuated by the revolving cam 27 driven by the usual timing gears from the engine in the usual manner. The push rod 26 actuates a rocker 25 arm 27 which is pivoted at 28 on the cylinder head and actuates the main air intake valve 29 through the valve stem 30. Mounted behind the push rod 26 and rocker arm 27 there is a similar rocker arm and connecting rod 30 for actuating an exhaust valve in the usual manner.

Mounted in the cylinder 31 there is a fuel injector plug 32 which extends downwardly therein and carries a fuel cup 33 on the 35 lower end thereof and the air and fuel valves for controlling the fuel supply to said fuel cup. The fuel cup 33 incloses a fuel chamber 34 which communicates with the passage 35 leading to the combustion 40 chamber 36 of the engine through the openings 37, of which there are usually two or three. For controlling and timing the injection of the fuel into the chamber 34, there is provided a valve 38 mounted on 45 the valve stem 39 which is maintained in normally closed position by the spring 40 mounted upon said valve stem. The valve stem extends through an air chamber 41 in said plug and communicates with the atmosphere through a small passageway 42 so as 50 to permit a small amount of air to enter the fuel chamber with the fuel. Extending at an angle to the valve stem 39, there is a fuel inlet passage 43 which communicates 55 with the fuel line 23, so that the liquid fuel passes down said passageway and communicates with the fuel chamber 44. Mounted in the fuel chamber 44, there is a needle valve 45 adapted to seat in a restricted opening 60 communicating with the fuel chamber 34 through the valve 38. The needle valve 45 is positioned on the end of a valve stem 46 which extends upwardly through the injector plug into an inclosing head 47. The 65 lower end of the valve stem 46 is surrounded

by a spring 48 which normally maintains said needle valve in closed position, and is of such diameter as will leave an appreciable space for the passage of fuel within the fuel chamber 44. The upper part of the 70 valve stem is hollow to provide a fuel passage 49 which communicates with the chamber 44 through the passageways 50, said upper portion containing within the passage 49 an actuating pin 51 adapted to be engaged by 75 the valve controlling lever 52. The head 47 incloses a fuel chamber 53 into which the fuel enters from the chamber 44 through the passages 49 and 50. The chamber 53 communicates with the overflow pipe 24 leading 80 back to the fuel reservoir. In communication with the chamber 53, there is an air vent attachment 54 for eliminating any suction which may be created within the fuel passageways by the passage of the fuel to 85 the reservoir.

Pivoted on the injector plug there is a lever 55 arranged to engage the valve stem 39 for actuating the fuel injection valve 38 at timed intervals, said lever being operated 90 through the connecting rod 56 which is pivoted at one end to the rocker arm 27 and at the other end to the lever 57, said levers 55 and 57 being connected through the bearing portion 58 of said plug. This causes 95 the valve 38 to open at timed intervals for admitting a new charge of fuel into the fuel cup 34. The amount of the fuel charged and admitted by said valve is controlled by the needle valve which is controlled through the lever 52 by the speed control hand wheel 59, or automatically by the governor 60 operating through the connecting rods 61 and 62, the rods 62 being connected to the 100 lever 52 through the arm 63.

In operation the fuel is first poured into the reservoir through the main filler pipe 64, and upon cranking the engine, it is pumped into the auxiliary tank 18 where it descends by gravity through the fuel line 23 and fuel passage 43 into the fuel chamber 44. The needle valve 45, being adjusted by the control wheel 59, admits a certain charge of fuel into the chamber 65, said 110 charge being in position to be admitted to the fuel chamber 34 when the valve 38 is actuated at the proper time. The air drawn by the suction of the engine into the chamber 41 is then admitted with the charge of 115 fuel when the valve 38 opens. This mixture of fuel and air then descends to the fuel chamber 34 where it is heated to such a degree by the compressed air in the combustion chamber that the more volatile parts of the fuel will be caused to ignite. The ignition of the vapor in said chamber 120 causes a small premature explosion which drives the heavier fuel out through the opening 37 in a substantially atomized condition, passing through the passageway 125 130 85

into the combustion chamber where the incandescent heat causes the burning thereof and the consequent expansion of the air for causing the power stroke of the piston. The 5 above operation of the engine is common to this type and is well known in the art. However, in using heavy fuels containing an appreciable percentage of gasoline, the intense heat about the valves 38 and 45 causes a gas to be formed within the fuel chamber 44 which lies around the needle valve and prevents the fuel from freely flowing therethrough by gravity with the consequent choking of the engine for lack 10 of fuel. To drive away this gas and keep it from forming at that point a system of circulation of the fuel is provided. By means of this arrangement the fuel entering 15 through the fuel line 23 passes by gravity through the fuel passage 43 into the chamber 44. Because of the high elevation of the auxiliary tank 18, or where no auxiliary tank is used and the fuel is pumped directly 20 into the injector head, such fuel as is not admitted through the needle valve 45 will pass up through the chamber 44, passageways 50 and 49 into the chamber 53 and out through the overflow pipe 24 and pipe 22 back to the reservoir. A continuous 25 circulating current of fuel will, therefore, be set up through the fuel chamber 44 so as to carry away any gas which may be formed therein about the valve 45. Such circulation of fuel will also carry away an appreciable amount of the heat generated about 30 said valve so as to maintain it in relatively cooled condition, and thereby reduce the amount of carbonization which would other- 35 wise be formed about said chamber and valve. 40

The invention claimed is:

1. In an engine, the combination of a combustion space, a vaporizing chamber, a valve for admitting liquid fuel to said chamber and having a recess in its upper end, a spring coiled about a reduced portion of said valve, a passage in which said valve is mounted, a control device for the valve, an enclosure for the control device, a source of fuel, and circulating means forcing fuel to said valve and including an inlet communicating with said passage and an outlet from the enclosure to said fuel source to permit the excess fuel to return to said source. 55

2. In an oil engine, the combination of a combustion space, a vaporizing chamber, a valve for admitting liquid fuel to said chamber having a recess in its upper end, a spring coiled about a reduced portion of 60 said valve, a passageway in which said valve is mounted, a control device for the valve, a closed compartment for said control device, a main fuel tank and an auxiliary fuel tank disposed above the main fuel tank, means for forcing fuel into said chamber from said auxiliary fuel tank, and means for passing unused fuel from said chamber to said main fuel tank comprising an outlet in said closed compartment and a 65 passageway from said outlet to said main fuel tank whereby circulation of oil is maintained around said fuel valve. 70

In witness whereof, I have hereunto affixed my signature.

CLESSIE L. CUMMINS.
